UNITED STATES PATENT OFFICE.

THOMAS E. MARTIN, OF DES MOINES, IOWA, ASSIGNOR OF ONE-HALF TO
GEORGE C. BOGGS, OF SAME PLACE.

BURGLAR-ALARM ATTACHMENT FOR WINDOWS.

SPECIFICATION forming part of Letters Patent No. 413,951, dated October 29, 1889.

Application filed March 29, 1889. Serial No. 305,280. (No model.)

To all whom it may concern:

Be it known that I, THOMAS E. MARTIN, a citizen of the United States of America, and a resident of Des Moines, in the county of Polk 5 and State of Iowa, have invented a Burglar-Alarm Attachment for Windows, of which the following is a specification.

My invention consists in the construction and combination of a roller, a bell, a striker, 10 and a lever for making the striker operative and inoperative at pleasure, with a frame or base adapted to be fixed to a window-sash, as hereinafter set forth, pointed out in my claims, and illustrated in the accompanying 15 drawings, in which—

Figure 1 is a side elevation, with part broken away, of my complete device ready to be applied. Fig. 2 shows sections of two window-sashes and my device attached as 20 required for practical operation. Fig. 3 is an end view of the base or frame having the bell, the striker, and the lever combined therewith.

a is a flat perforated base adapted to be 25 fixed upon the top of a sash by means of common screws.

b is a post or roller-bearer that projects perpendicularly from one edge of the base *a*.

c is a corresponding bearer on the oppo- 30 site edge of the plate.

d is a curved post pivoted to the base *a* to support a bell.

f is a roller placed upon an axle *g*, fixed to the parallel bearers *b* and *c*.

f' is an elastic ring fixed over the periphery of the roller.

h is a circular flange on the side face of the roller, and 1 2 3 4 are catches at the ends of inclined planes in the side face or edge of the 40 flange.

m is a striker connected with the fixed axle-bearer *b* by means of a coiled spring-wire *n* in such a manner that the spring-wire will in its normal condition retain the 45 striker close to but not in contact with the inside of the bell.

r is a bell fixed to the top of the bearer *d* in such a manner that it will practically cover the roller and base.

s is an elbow-shaped lever pivoted on top 50 of the base *a* in such a manner that its vertical portion can be adjusted relative to the spring-stem *n* of the striker and the catches 1 2 3 4 on the side of the roller.

In the practical operation of my invention 55 when applied to a window, the raising of the lower sash or the lowering of the upper sash will, by the contact and friction of the upper sash with the periphery of the roller, rotate the roller in such a manner that the catches 60 1 2 3 4 will successively engage and lift the spring and striker, and the vertical portion of the lever *s* will perform the function of a cam and throw the spring *n* off the catches and free the force stored in the elevated spring 65 to be exerted in beating the striker upon the bell as required to ring it and sound an alarm.

To make the striker inoperative I move the lever so that its vertical portion will press against the spring *n* sufficiently to hold it 70 away from the roller, as required, to allow the roller to rotate without catching and lifting the spring and striker.

I am aware that a roller having a ratchet on its side face has been combined with a bell and 75 a base adapted to be fixed to a window-sash by means of a hinged post and a hinged roller-bearer; but my manner of constructing a frame and combining a roller, a bell, a striker, a lever, and a spring therewith is novel and 80 greatly advantageous, in that it can be readily applied and made operative or inoperative at pleasure. By turning the lever so as to project at right angles to the bell it will press the spring-stem of the hammer and re- 85 main stationary, as required, to retain the hammer inoperative while one of the windows is moved and the roller rotated, or by simply pressing against the outer end of the lever with a finger while raising or lowering 90 a sash the striker will be retained inoperative until the pressure of the finger is relaxed. Windows can be thus moved up or down by a person on the inside without sounding the bell or giving an alarm.

95 I claim as my invention—

1. A burglar-alarm and window attachment comprising a base *a*, having posts *b* and

at its sides, a roller having a series of catches 1 2 3 4 in bearings at the tops of said posts, a curved post *d* between said posts, a bell fixed to the curved post, a striker *m*, having a spring-stem *n* fixed to one of the side posts, and a lever *s*, pivoted on top of the base, constructed and combined to operate in the manner set forth.

2. The base *a*, having fixed posts *b* and *c* at its sides, the roller *f*, having a series of catches on its side face in bearings at the tops of said posts, a curved post *d* between

the posts *b* and *c*, a bell fixed to the said curved post, a striker having a spring-stem fixed to one of the side posts, and an elbow-shaped lever pivoted on top of the base, constructed and combined and attached to the top of a window-sash to operate in the manner set forth, for the purposes stated. 15

THOMAS E. MARTIN.
